UNITED STATES PATENT OFFICE.

CHARLES D. LAYMAN, OF LOUISVILLE, KENTUCKY.

EXERCISER.

Application filed March 3, 1924. Serial No. 696,633.

To all whom it may concern:

Be it known that I, CHARLES D. LAYMAN, a citizen of the United States, and a resident of Louisville, in the county of Jefferson, State of Kentucky, have invented a new and useful Improvement in Exercisers, of which the following is a full, clear, and exact description.

My invention relates to improvements in exercisers, and it consists in the combinations, constructions, and arrangements herein described and claimed.

An object of my invention is to provide an exerciser of the character described which is intended to give beneficial effects of rowing.

A further object of my invention is to provide an exerciser of the type described which may be manufactured at very little expense, thus permitting the ordinary person not having access to a fully equipped gymnasium to have the benefits of a rowing machine in his or her own home.

A further object of my invention is to provide an exerciser of the type described in which novel means is employed for varying the resistance offered by the exerciser, so as to accommodate the device for use by children or grown persons.

A further object of my invention is to provide a device of the type described which is extremely compact in form, so that when the exerciser is not in use, it may not encumber the premises upon which it is kept.

Other objects and advantages will appear in the following specification, and the novel features of the invention will be particularly pointed out in the appended claims.

My invention is illustrated in the accompanying drawings forming part of this application, in which—

Figure 1 is a front elevation of an embodiment of my invention.

Figure 2 is an enlarged side elevation of a part of the mechanism illustrated in Figure 1.

Figure 3 is a top plan view of the mechanism illustrated in Figure 2.

Figure 4 is an end elevation of a modified form of my invention, and

Figure 5 is a sectional view along the line 5—5 of Figure 4.

In carrying out my invention I make use of a suitable supporting surface such as a door 1. My purpose in choosing a door is so that when the door is folded and moved

back against the wall the exerciser is entirely out of sight. A bracket 2 is secured by means of wood screws or the like adjacent the top of the door 1. This bracket 2 is provided with a horizontal rod 3 having compression springs 4 and 5 secured at opposite ends thereof, and arranged to lie in a substantially vertical plane.

The lower ends of the compression springs 4 and 5 are provided with T-shaped connecting members 6. These connecting members 6 are each connected with a pair of flexible cables 7.

Each pair of cables 7 is wrapped once around a friction drum hingedly supported at the lower end of the door 1. These friction drums are more fully illustrated in Figures 2 and 3, and consist in a body member 8 having a pair of drum members 9 formed by drawing the inner portion of steel discs 10 inwardly, secured to each side of the body member 8 by means of a fastening means 11, which may be the ordinary type of machine bolt and nut. The body member 8 is hingedly mounted upon a fastening plate 12 by means of a bolt 13 in the manner shown in Figure 2. The purpose of mounting the body member 8 upon the hinged support is so that the drum element may swing from one side to another, and thus follow the natural arm movements of the operator during the process of exercising, so that the cables may not become frayed through contact with the peripheral edges of the discs 10 and the peripheral edge of the body member 8.

The outer ends of each pair of cables 7 have hand grips 14 secured thereto so that the cables may be grasped by the hand at their lower ends and drawn away from the drums against the action of the springs 4 and 5. It should be noted that the cables 7 are wrapped about the drawn portions 9 of the drums once, so as to increase the snubbing effect occasioned by friction as the cables are drawn over the drums.

In this embodiment of my invention I have produced an exerciser in which movement of the cables 7 is a relatively short movement, similar to the stroke of an oar, as in rowing, but if it is desired to increase the movement of the cables, then the ordinary type of block and tackle used in the gravity exercising devices may be employed. For all ordinary purposes, however, the form

I have shown in Figure 1 is particularly well suited. The operator may either stand or assume a sitting position while using the device. It is suggested that a sitting position would bring about the rowing effect more completely than if it were necessary to draw the arms upwardly as in a standing position.

From the foregoing description of the various parts of the device, the operation thereof may be readily understood. In order to accommodate my improved exerciser to the muscular capabilities of the person using the device, the exerciser should first be adjusted for that person. This may be done by any of two different ways. First, by elevating or lowering the plate 2 upon the door 1, and second, by engaging the cables 7 with the drums. Instead of passing the cables once about each of the portions 9 of the drums, the cable may be passed twice around, if the person using the exerciser is particularly vigorous and strong. Once around the drums is sufficient for the ordinary person. If a child is to use the device, or a person not possessing the normal strength of an adult, the cables 7 may be passed under the drums and not wrapped about the drum. In this manner, the force required to draw the cables 7 against the actions of the springs 4 and 5 may be varied at will.

In using my improved exerciser the operator may assume a sitting position and press the feet upon the door 1, or upon the floor and grasp one of the hand grips 14 in each hand. The movement of the arms is practically identical to the movement of the arms of a person rowing a boat. There is sufficient drag upon the cables as they pass over the drum to resist quick movement, but to permit a slow steady pull. When the hand grips 14 are drawn sufficiently away from the door 1, the arms of the operator must permit some slack of the cables between the hand grips and the drums, whereupon the springs 4 and 5 will draw the cables back to their original position, whereby they are ready for another stroke.

In Figures 4 and 5 I have shown a modified form of the invention, in which I do away with the springs 4 and 5, and substitute the voluntary muscular force of a person. In this manner, two persons may benefit by the use of the device at the same time. To this end I provide a platform 15 having a seat portion 16 at each end thereof. A pair of parallel drum supporting members 17 is disposed at each side of the platform at its mid point. Suitable foot boards 18 are disposed transversely to the drum supporting members 17 so that a person sitting

upon the seats 16 may place his feet upon the foot boards 18 and thereby brace himself against the force exerted by the opposite person pulling upon the cables 7. In this form of the invention hand grips 14 are disposed at each end of the pairs of cables 7. The body member or central portion 8 of the drums is not provided with a hinged support 12, but the drums are mounted rigidly upon the drum supporting members 17 by the projection of a bolt 19 in place of the bolt 11, which is also projected through the supporting member 17.

The operation of this form of my invention is practically the same as that of the preferred form, except that two persons may use the device at the same time, one pulling the cables 7 toward himself while the opposite person exerts just enough tension upon the cables to satisfy the person drawing the cable, or simulating the movement of the rowing stroke. In this form of the invention, the operators alternately take a rowing stroke and a return stroke, the return stroke being retarded sufficiently to hold the cables taut.

I claim:

1. An exerciser of the type described, a non-rotatable friction drum, means for hingedly mounting said drum upon a supporting surface, a flexible cable arranged for frictional engagement with said drum, a hand grip associated with said cable at one end thereof, and means for opposing the movement of said cable in one direction associated with the opposite end of the cable.

2. An exerciser of the type described comprising a non-rotatable drum, means for hingedly mounting said drum on a supporting surface, a pair of cables arranged for frictional engagement with said drum, a spring for resisting the movement of said cable in one direction, and a hand grip carried by the opposite end of said cable.

3. An exerciser of the type described comprising a friction drum having its peripheral wall separated by a radially extending flange extending the entire circumference of the drum, thereby dividing said friction drum into two parts, means for securing said drum to a supporting surface, a pair of flexible cables frictionally engaged with the surfaces of said drum on either side of said flange by winding said cables around said drum, a hand grip associated with adjacent ends of said cables, and means for opposing the movement of said cables in one direction associated with the opposite ends thereof.

CHARLES D. LAYMAN.
